UNITED STATES PATENT OFFICE.

GEORGE L. MEIER, OF CALDWELL, NEW JERSEY, ASSIGNOR TO THE NEW YORK LIGHTING FIXTURE MFG. CO., A CORPORATION OF NEW YORK.

DESIGN FOR A BACKPLATE FOR LIGHTING FIXTURES.

Application filed September 16, 1926. Serial No. 19,087. Term of patent 3½ years.

To all whom it may concern:

Be it known that I, GEORGE L. MEIER, a citizen of the United States, and a resident of Caldwell, county of Essex, and State of New Jersey, have invented a new, original, and ornamental Design for a Backplate for Lighting Fixtures, of which the following is a specification, reference being had to the accompanying drawing, forming a part thereof.

In these drawings:

Figure 1 is a front elevational view of the back plate for lighting fixtures; and

Figure 2 is a diagrammatic side outline view of the same.

I claim;

The ornamental design for a backplate for lighting fixtures substantially as shown.

GEORGE L. MEIER.
